UNITED STATES PATENT OFFICE.

HALVER R. STRAIGHT, OF ADEL, IOWA.

KILN AND SIMILAR STRUCTURE.

1,290,848.

Specification of Letters Patent.

Patented Jan. 7, 1919.

Application filed November 11, 1916. Serial No. 130,800.

To all whom it may concern:

Be it known that I, HALVER R. STRAIGHT, a citizen of the United States, residing at Adel, in the county of Dallas and State of Iowa, have invented new and useful Improvements in Kilns and Similar Structures, of which the following is a specification.

The object of my invention is to secure efficiency and durability in kilns and similar structures by simple and economical means.

More particularly, it is my object to provide in a kiln a composite wall having a resilient and heat insulating packing between inner and outer shells, said arrangement being adapted to compensate for the unequal expansion and contraction of said shells.

These and other objects will more fully hereinafter appear.

In the drawings, Figure 1 is a composite view, the part at the left showing a vertical section of a portion of the kiln, while the part at the right of said view illustrates in elevation a portion of the inner shell and a fragment of the outer shell, the former being broken away to show the connections between several horizontal reinforcing rods and one of the door frames; Fig. 2 is a detail sectional view taken on the line 2—2 of Fig. 1; Fig. 3, is a detail view showing a portion of the outer reinforcing wall; Fig. 4 is a sectional view taken on the line 4—4 of Fig. 3; and Fig. 5 is a plan view of a hollow building tile employed to make up the permanent form for the outer reinforced shell.

Referring to the drawings, it will be seen that my improved kiln consists of a composite wall A comprising an inner shell 10, a reinforced outer shell 11 and intermediate heat insulating packing 12 which is composed of resilient and loose material, such as mineral wool or cinders. A crown 13 is carried upon the inner shell 10. Doorways 14 penetrate the composite wall and are supplied with metal doorframes 15. Each doorframe consists of an arched member 16 formed with a flange 17 overlapping the outer shell 11 and provided with a sill 18 and stay-rods 19. The inner shell 10 is constructed of brick in the usual manner, but is thinner than the ordinary kiln wall. Said inner shell 10 is supplied with a rein-

forcing band 20 at its upper margin to support the thrust of the arched crown 13. The frame of the outer shell 11 is constructed of hollow building tile 21, which are formed and arranged to receive vertical and horizontal reinforcing rods embedded in grouting material, such as concrete, which elements, when united as hereinafter described, constitute a rigid and durable unitary structure. As shown, these hollow tile 60 have four cells and are arranged vertically end-on-end in staggered relation, so that the cells therein register and form vertical openings extending from the bottom of the shell 11 to the top thereof. A reinforcing rod 22 70 is placed within each of these openings and concrete 23, or the like, is poured therein, the rod 22 being used as an agitator to settle said concrete. Transverse grooves 24 in the upper ends of the tile 21 form horizontal recesses in which reinforcing rods 25 are placed. At opposite sides of the doorways 14, these rods are secured to keepers 26 attached to the doorframe 15. Said rods are preferably bent to form hooks 27 (Fig. 2) 80 which engage said keepers. The spaces between the building tile 21 and the members 16 of the doorframes 15, which contain the hooks 27 and keepers 26, are filled with concrete after said hooks have been secured in 85 said keepers.

The outer shell 11 extends considerably above the inner shell 10 and the loose insulating packing 12 is carried above said inner shell and about the margin of the crown 90 13. A seal or covering 28, consisting of fire clay, or other suitable fireproof material, is placed over the insulating packing 12 and is adapted to expand or contract without disintegrating, thereby excluding moisture 95 from the packing 12. To protect this covering 28, I provide a deck 29 of brick, or other fireproof material, which is set upon an incline and adapted to drain water from the top of the kiln.

The width of the space between the shells 10 and 11 is determined with respect to the compressibility of the packing therein, so that it may be of sufficient thickness to compensate for the expansion of the inner shell. 105

It will be noted that this loose packing 12 not only insulates and permits the expansion of the inner shell 10, but also presses inwardly against said shell and follows it while assuming normal dimensions when 110

contracting, thereby minimizing the racking of said inner shell due to changes in temperature.

Having described my invention, what I claim as new and desire to protect by Letters Patent, is:

1. In a structure of the class described, a composite wall comprising inner and outer shells, a heat insulating packing of loose resilient material between said shells, a reinforcement for the top of the inner shell, and a crown supported upon said shell.

2. In a structure of the class described, an annular composite wall comprising an inner shell or lining, an outer reinforced shell surrounding said inner shell, an insulating resilient packing loosely interposed between said shells, a crown supported upon said inner shell, and a reinforcing band around the top of said inner shell to support the thrust of the crown.

3. In a structure of the class described, a wall comprising two independent concentric shells spaced apart from each other, a filler of resilient insulating material between said shells, and a crown supported upon one of said shells.

4. In a structure of the class described, a wall, a crown supported upon the wall, said wall including an inner shell, and a reinforced outer shell formed of hollow building blocks arranged end-to-end in staggered relation and containing reinforcing rods and a grouting material to form a rigid unitary structure, and a resilient insulating material loosely interposed between said outer and inner shells, said material permitting free expansion and contraction of said inner shell.

40 5. In a structure of the class described, a wall having doorways therein and doorframes therefor, and a crown supported upon the wall, said wall including an expandible fireproof inner shell and a rigid outer shell having reinforcements therefor consisting in part of said doorframes, and

a resilient insulating material loosely interposed between said outer and inner shells, said material permitting free expansion and contraction of said inner shell.

50 6. In a structure of the class described, an inner shell, a crown supported thereon, an outer shell spaced apart from and surrounding said inner shell, a filler of loose insulating material between said shells and a compensating seal covering the filler.

55 7. In a structure of the class described, two concentric walls, the inner wall being of fireproof material and the outer wall comprising hollow tile having reinforcing rods extending therethrough and a grouting material within said tile, incasing said rods, whereby rigidity is imparted to said outer shell, a loose resilient insulating material between said shells, said material compensating for unequal expansion of said inner and outer shells, and a crown on said inner shell.

60 8. In a structure of the class described, a reinforced self-compensating wall having a doorframe therein and being formed of inner and outer shells, said inner shell being expandible and said outer shell formed of hollow tile, reinforcing means for said tile comprising horizontal and vertical rods, certain of said horizontal rods being attached to said doorframe, a grouting material within said hollow tile, a filler of loose insulating material between said shells, and a crown supported by said wall.

65 9. In a structure of the class described, a wall having outer and inner shells, the former being higher than the latter, a crown supported upon the inner shell, loose insulating material placed between said shells and surrounding the margin of said crown, and a moisture excluding covering for said insulating material.

70 Whereof I have hereunto subscribed my name to this specification.

HALVER R. STRAIGHT.
